DESIGN FOR A CASKET REST

Lawrence C. Haaser, Bucyrus, Ohio, assignor to
The Sozonian Vault Company, Bucyrus, Ohio,
a corporation of Ohio

Application December 14, 1938, Serial No. 81,774

Term of patent 7 years

To all whom it may concern:

Be it known that I, Lawrence C. Haaser, a citizen of the United States, a resident of Bucyrus, Crawford County, Ohio, have invented a new, original, and ornamental Design for a Casket Rest, of which the following is a specification, reference being had to the accompanying drawing, forming a part thereof.

In the drawing:

I claim:

The ornamental design for a casket rest, as shown.

LAWRENCE C. HAASER.
